UNITED STATES PATENT OFFICE.

SIMON HEITER AND SALOMON J. LESEM, OF NEW YORK, N. Y.

DESIGN FOR AN UMBRELLA-HANDLE.

SPECIFICATION forming part of Design No. 11,694, dated March 23, 1880.

Application filed February 5, 1880. Term of patent 3½ years.

To all whom it may concern:

Be it known that we, SIMON HEITER and SALOMON J. LESEM, citizens of the United States, and both residing at New York, in the county and State of New York, have invented and produced a new and original Design for Parasol and Umbrella Handles, of which the following is a specification, reference being had to the accompanying drawing, forming part thereof.

The special feature of our design consists in a branching head having ornamental embossments thereon.

The accompanying drawing illustrates, in a side view, our newly-designed handle.

a represents the body or lower part of the handle, which may be of any form preferred. *b* *c* are branches springing from the top and center of the handle, and spreading out in opposite directions. The curvature of both is similar; but the branch *b* is considerably longer than the branch *c*.

From the tip of the short branch *c* rises an embossment, *d*, somewhat oval-shaped, the sides *d'* *d'* of which are convex. From the branch *b* rises a series of oblong-shaped embossments, *e* *e*, &c., decreasing in size and height from *e'* to the tip of the branch, so that

the outer or upper edge of the embossments will be on the same plane with the embossment *d*. 30

The embossments rising from the branch *b* are of long tapering shape, with ball-shaped tips, the outer contour of which forms, as a whole, a scalloped or inuated outline. 35

Any one or all of the embossments may be made of the same or of a material different from that composing the body of the handle.

We claim—

1. The design for an umbrella or parasol handle, consisting of the divergent branches *b* and *c*, spreading out from the top of the handle, and the ornamental embossment *d*, as described, and shown in the accompanying drawing. 40

2. The design for an umbrella or parasol handle, consisting of the branches *b* and *c* at the top of the handle, with embossments *e* *e* and *d*, the contour of the same being on a horizontal plane, as described, and shown in 50 the accompanying drawing.

SIMON HEITER.
SALOMON J. LESEM.
